CORNER GUARD FOR FURNITURE OR THE LIKE

Benjamin Finebaum, Memphis, Tenn., assignor to Creativity Unlimited, Corp., Memphis, Tenn.

Filed Mar. 17, 1969, Ser. No. 16,262

Term of patent 3½ years

Int. Cl. D6—99

U.S. Cl. D33—1

FIG. 2

FIG. 5

FIG. 1

FIG. 3

FIG. 4

FIG. 7

FIG. 6

FIG. 1 is a top plan view of a corner guard for furniture or the like showing my new design.

FIG. 2 is a side elevational view taken from the upper portion of FIG. 1.

FIG. 3 is a side elevational view taken from the right hand side of FIG. 1.

FIG. 4 is a front elevational view taken from the lower portion of FIG. 1.

FIG. 5 is a side elevational view taken from the left hand side of FIG. 1.

FIG. 6 is a bottom plan view thereof.

FIG. 7 is an auxiliary view taken from the lower left hand corner of FIG. 1.

I claim:

The ornamental design for a corner guard for furniture or the like, as shown and described.
